UNITED STATES PATENT OFFICE.

CHARLES G. GLADDEN, OF MARION, NORTH CAROLINA.

PRESS.

Application filed November 10, 1921. Serial No. 514,355.

To all whom it may concern:

Be it known that I, CHARLES G. GLADDEN, a citizen of the United States, residing at Marion, in the county of McDowell and State of North Carolina, have invented a new and useful Improvement in Presses, of which the following is a specification, reference being had to the accompanying drawing.

10 My improvement relates particularly to presses in which both pressure and heat are applied to the material which is being treated. My press is specially designed for drying or redrying wood veneer. In the operation 15 of drying wood veneer, it is desirable that the pressure be applied during only short periods, in order that the sheets may shrink, due to drying, while the sheets are not held between the press plates with such force as 20 will lead to the splitting of the sheets during contraction. The object of my invention is to produce an automatic press wherein numerous wood veneer sheets may be repeatedly automatically subjected to pressure 25 and heat during short periods, until the sheets have been sufficiently dried or redried and pressed to make them ready for use.

My press includes, among other elements, a series of horizontal plates or platens between which the veneer sheets are to be 30 pressed. The alternate plates are placed in relation with power mechanism for raising and lowering said plates. When lifted, said plates make contact with and lift the other 35 plates. During downward movement of the first set of plates, every plate of the second set is arrested and held by stationary means. During the further downward 40 movement of the plates of the first set, every plate of the first set makes contact with and is arrested by the next lower plate, now stationary, of the second set. The power mechanism which is in operative relation with the plates of the first set operates continuously, after being set in motion, until 45 it is stopped by the operator. Thus said first set of plates are put through their movements automatically. The time during which there is contact between plates may 50 be varied as hereinafter explained.

In the accompanying drawings,

Fig. 1 is a front elevation of a machine embodying my improvement, the middle part being broken away and the cranks being in their middle positions;

Fig. 2 is an elevation of the left hand end of the same machine;

Fig. 3 is an elevation of the right hand end of the same machine;

Fig. 3^a is a detail elevation;

Fig. 4 is a plan of the same machine, the middle part being broken away;

Fig. 5 is a horizontal section on the line, 5-5, of Fig. 2;

Fig. 6 is a horizontal section on the line, 6-6, of Fig. 2;

Fig. 7 is an upright section on the line, 7-7, of Figs. 2 and 4;

Fig. 8 is an upright section on the line, 8-8, of Fig. 2, looking toward the left.

In said drawings, A, A, A, A are upright corner posts forming parts of the frame of the machine. In the form shown by the drawings, these posts are of angle iron or steel. At each end of the machine 75 are three horizontal end pieces, A¹, one near the base of the corner posts, one at the upper ends of the corner posts and another near the upper ends of the corner posts, and all secured immovably to the corner posts by 80 means of bolts or rivets, A². These end pieces are in the form of channel iron. Near the lower ends of the corner posts, front and rear horizontal frame pieces, A³, have their ends joined to the adjacent corner posts by means of bolts or rivets, A⁴. These pieces are also channel form. On the upper end of the corner posts rest front and rear frame pieces, A⁵, of angle-form cross section, said pieces being joined to the corner posts by bolts or rivets, A⁶.

To provide more seating surface for the frame pieces, A⁵, a bracket, A⁷, is placed into the angle of each corner post, the upper face of the bracket being brought even 95 with the upper face of the post. Bolts or rivets, A⁸, extend through said bracket and the adjacent corner post, A, as well as the adjacent frame member, A⁵. Four cross pieces, A⁹, are placed with their ends resting on the front and rear members, A⁵, the cross members being secured to the members, A⁵, by bolts or rivets, A¹⁰. Said cross members are arranged in pairs suitably spaced to support shaft bearings and to 100 receive spur gear wheels between them, as will appear further on.

In the front and rear flanges of the corner posts, A, are upright slots A¹¹, the slots in one of said posts being at the levels of the 110

corresponding slots in the other posts. Horizontal bars, B^1 , extend from one post to the other and have their ends resting loosely in slots which are at the same level. Idle platens or plates, B , are supported by said bars, the ends of the plates abutting against the bars, B^1 , and screw bolts, B^2 , joining said bars to the platens. In the form shown in the drawings, the bolts extend through the bars and are threaded into the platen. The platen is of proper width, from front to rear, to bring its edges close to the inner faces of the adjacent flanges of the corner posts, whereby the platen is held against forward or backward movement but to permit up-and-down movement. The slots, A^{11} , are upright and higher than the height of the bars, B^1 , so that said bars are permitted to move up-and-down only. Thus endwise movement of the platen is prevented. This is all the support that the platens, B , have. The slots, A^{11} , are spaced far enough from each other to allow the placing of active platens in alternation with the idle platens, B .

C , C are the active platens. They are so termed because they are active and in direct relation with the power mechanism. Said platens are of the same length and width as the platens, B , so that their front and rear edges are also guided by the front and rear flanges or webs of the corner posts. At each end of the machine upright hangers bars, C^1 , extend across the ends of all of the platens, C , and are secured thereto by bolts, C^2 , extending into spacing bosses, C^2 , formed on the platen behind the bars, C^1 , in order that the bars, B^1 , and the bars, C^1 , will not engage each other sufficiently to prevent free movement of the platens relatively to each other.

The bars, C^1 , are shown extending between the platens B and C , and the adjacent flanges of the corner posts, in order that said bars may bear against the inner face of said flange for holding the platens C , against endwise movement. At each end of the machine, the lower ends of the bars, C^1 , are bent toward each other and coupled to the ends of a horizontal yoke, C^3 , by bolts C^4 . A suspension rod, C^6 , extends slidably through an upper bearing, C^5 , at the middle of said yoke. Said suspension rods also extend slidably through bearings, C^7 , on the lower two horizontal end pieces, A^1 . The lower end of each rod, C^6 , is surrounded by a nut, C^8 , which is adjustable up-and-down on said rod. The upper end of each rod is coupled to the lower end of a pitman, C^9 , the upper end of which is coupled to a crank wheel, C^{10} , which is fixed on a horizontal transmission shaft, D , which rests in bearings, D^1 , which rest on the upper faces of the frame cross members, A^9 . Between the bars of each pair of bars, A^9 , a spur gear wheel, D^2 , surrounds and is fixed to said shaft and meshes with a smaller spur gear wheel, D^3 , which is fixed on the shaft, D^4 , which is parallel to the shaft, D , and rests in bearings, D^5 , which rest on the bars, A^9 . One end of the shaft, D^4 , projects beyond the end of the machine and supports a drive pulley, D^6 , with which is associated an ordinary clutch, D^7 , by means of which the drive pulley may be engaged for transmission of power from the drive pulley to said shaft. When the drive pulley has been engaged by the clutch, the shaft, D^4 , turns continually and uniformly and transmits similar but slower motion to the shaft, D . By the rotation of said shaft, the crank wheels, C^{10} , are continually and uniformly rotated. Such rotation results in the continual reciprocation of the suspension rods, C^6 , said rods sliding in the bearings, C^7 .

The plates or platens, B , may be regarded as normally at rest, the bars, B^1 , resting in the lower parts of the slots, A^{11} . During the downward movement of the suspension rods, the plates or platens, C , move downward with said rods as fast as permitted by the yokes, C^3 , the latter being supported by the nuts, C^8 , on the lower ends of the suspension rods. The length of said rods and the positions of the nuts on said rods are such as to cause the platens, C , to meet and bear upon the upper faces of the platens, B , before said rods reach their lower limit. Then, said rods slide also in the bearings, C^7 , the platens, C , resting on the platens, B . This movement continues until the cranks again resume their upward movement, the nuts, C^8 , having moved away from the yokes (see Fig. 3). Then the suspension rods are lifted until the nuts, C^8 , again engage the lower faces of the yokes, C^3 , and lift said yokes. This causes the lifting of the bars, C^1 , and the platens, C , until the cranks have again reached their upper limit. The various parts are so proportioned and positioned as to cause the upper faces of the platens, C , to bear against the lower faces of the platens, B , during the latter part of the upward movement of the platen, C , whereby every platen, C , lifts the platen, B , which rests immediately above that platen, C . During the continuation of the turning of the crank wheel, the suspension rods again descend and allow the platens, C , and the platens, B , supported by the platens, C , to descend, until the downward movement of the platens, B , is arrested by engagement of the bars, B^1 , in the lower parts of the slots A^{11} . But the downward movement of the platens, C , continues until the lower faces of said platen again meet and bear upon the upper faces of the next lower platens, B , whereby the platens, C , are held at rest on the platens, B , until the upward movement of the suspension rods has again proceeded far enough to cause the lifting of the yokes, C^3 , whereby the platens, C , are again lifted. Thus the movements of the suspension rods and of the platens continue as long as

the clutch, D⁷, engages the drive pulley, D⁶. Veneer sheets lying between the platens will be repeatedly pressed and released, the duration of pressure and the intervals of time between periods of pressure depending upon the velocity of the shaft, D, and the proportions of the various parts. The degree of pressure exerted upon the veneer sheets will depend upon the area and weight 10 of the platens.

From the foregoing it will be seen that the platens, B, are independent of each other and that during the upward movement of the platens, C, whereby the platens, 15 B, are lifted every platen, B, is free to adjust itself individually on the upper face of the next lower platen, C. If such separate adaptability for the platens, C, while they rest on the platens, B, is desired, the 20 holes in the hanger bars, C¹, through which the bolts, C², extend, may be made a little larger than the thickness of the bolts, in order that every bolt may have a little up-and-down movement in the bar through 25 which said bolt extends. (See Fig. 8.)

Any desired number of the platens are to be heated. For this purpose, these platens are made hollow and provision is made for circulating steam or hot water through 30 the platens. In the form of the apparatus shown by the drawings, provision is made for thus heating all the platens. The platens are chambered or hollow. At the right hand end of the machine, branch intake 35 pipes, C¹¹, are tapped into the end of every platen, C, near its rear edge, and an exhaust branch pipe, C¹², is similarly tapped into the end of every platen near its forward edge. All the branch pipes, C¹¹, are joined 40 to a main supply pipe, C¹², and all the exhaust branch pipes, C¹³, are connected to a main exhaust pipe, C¹⁴. At the left hand end of the machine, corresponding branch pipes and main pipes, bearing corresponding 45 symbols, are similarly applied to the left hand ends of the platens, B. These branch pipes and main pipes are arranged in any well known manner to permit up-and-down movement simultaneously with 50 the up-and-down movements of the platens.

By arranging the pipes and the hanger bars and the suspension rods at the ends of the machine, the front and rear of the machine are left clear for the insertion and 55 removal of veneer sheets into and out of the spaces between the platens. To facilitate engaging the veneer sheets by the hands of the operator, notches, E, are formed in the front and rear edges of the platens.

60 The length of time during which the intermittent movements of the platens are to be continued and the veneer sheets are to remain in the press will depend upon the thickness of the veneer sheets and the condition, as to moisture, of the veneer sheets

at the beginning of the operation and whether the sheets are to be given a preliminary drying or a final drying.

I claim as my invention,

1. In an apparatus of the nature described, the combination of a group of horizontal idle platens supported to permit up-and-down movement and spaced from each other sufficiently to leave between them spaces greater than the thickness of the below-mentioned active platens, active platens alternating with the idle platens and adapted to rest by gravity on the latter, and means for intermittently reciprocating the active platens to cause said platens to bear 70 upward against and lift the next higher idle platens, and then to descend until the lifted idle platens are again engaged by and rest on their supports and until the active platens again rest upon the next lower idle 75 platens, substantially as described.

2. In an apparatus of the nature described, the combination of a group of horizontal idle platens supported to permit up-and-down movement and spaced from each 80 other sufficiently to leave between them spaces greater than the thickness of the below-mentioned active platens, active platens alternating with the idle platens and adapted to rest by gravity on the latter, 85 means joining said active platens to hold said platens as a group for substantially simultaneous up-and-down movement, and means for periodically reciprocating said group of platens to cause each platen of said 90 group to bear upward against and lift the next higher idle platen, and then to descend until the lifted idle platens are again engaged by and rest on their supports and until every active platen again rests upon the 95 next lower idle platen, substantially as described.

3. In an apparatus of the nature described, the combination of a group of horizontal idle platens supported to permit up-and-down movement and spaced from each other sufficiently to leave between them spaces greater than the thickness of the below-mentioned active platens, active platens alternating with the idle platens and 100 adapted to rest by gravity on the latter, means for intermittently reciprocating the active platens to cause said platens to bear upward against and lift the next higher 105 idle platens, and then to descend until the lifted idle platens are again engaged by and rest on their supports and until the active platens again rest upon the next lower idle platens, and means for heating said 110 platens, substantially as described.

4. In an apparatus of the nature described, the combination of a group of horizontal idle platens supported to permit up-and-down movement and spaced from each other sufficiently to leave between them 115

spaces greater than the thickness of the below-mentioned active platens, active platens alternating with the idle platens and adapted to rest by gravity on the latter, 5 means joining said active platens to hold said platens as a group for substantially simultaneous up-and-down movement, means for periodically reciprocating said group of platens to cause each platen of said 10 group to bear upward against and lift the next higher idle platen, and then to descend until the lifted idle platens are again engaged by and rest on their supports and until every active platen again rests upon 15 the next lower idle platen, and means for heating said platens, substantially as described.

5. In an apparatus of the nature described, the combination of a group of horizontal idle platens supported to permit up-and-down movement and spaced from each other sufficiently to leave between them spaces greater than the thickness of the below-mentioned active platens, active platens 20 alternating with the idle platens and adapted to rest by gravity on the latter, a rotary shaft in operative relation with the active platens to periodically reciprocate the active platens to cause said platens to bear upward against and lift the next higher idle platens, and then to descend until the lifted idle platens are again engaged by and rest on their supports and until the active platens again rest upon the next lower 25 idle platens, and means for heating said platens, substantially as described.

6. In an apparatus of the nature described, the combination of a group of horizontal idle platens supported to permit up-and-down movement and spaced from each other sufficiently to leave between them spaces greater than the thickness of the below-mentioned active platens, active platens 30 alternating with the idle platens and adapted to rest by gravity on the latter, upright reciprocatory suspension rods in operative relation with the active platens to periodically reciprocate the active platens to cause said platens to bear upward against and lift the next higher idle platens, and then to descend until the lifted idle platens are again engaged by and rest on their supports and until the active platens again rest upon the next lower idle platens, and means for heating said platens, substantially as described.

7. In an apparatus of the nature described, the combination of a group of horizontal idle platens supported to permit up-and-down movement and spaced from each other sufficiently to leave between them spaces greater than the thickness of the below-mentioned active platens, active platens 40 alternating with the idle platens and adapted to rest by gravity on the latter, upright reciprocatory suspension rods in operative relation with the active platens to cause each platen of said group to bear upward against and lift the next higher idle platen, and then to descend until the lifted idle platens are again engaged by and rest on their supports and until every active platen again rests upon the next lower idle platen, and means for heating said platens, substantially as described.

8. In an apparatus of the nature described, the combination of a group of horizontal idle platens, upright corner posts formed for supporting said platens with spaces between them greater than the thickness of the below-mentioned active platens, active platens 45 alternating with the idle platens and adapted to rest by gravity on the latter, means for periodically reciprocating the active platens to cause said platens to bear upward against and lift the next higher idle platens, and then to descend until the lifted idle platens are again engaged by and rest on their supports and until the active platens again rest upon the next lower idle platens, and means for heating said platens, substantially as described.

9. In an apparatus of the nature described, the combination of a group of horizontal idle platens, laterally directed bars on said platens, upright corner posts having 50 slots for receiving said bars, active platens alternating with the idle platens and adapted to rest by gravity on the latter, means for periodically reciprocating the active platens to cause said platens to bear upward against and lift the next higher idle platens, and then to descend until the lifted idle platens are again engaged by and rest on their supports and until the active platens again rest upon the next lower idle platens, and means for heating said platens, substantially as described.

10. In an apparatus of the nature described, the combination of a group of horizontal idle platens, laterally directed bars on said platens, upright corner posts having 55 slots for receiving said bars, active platens alternating with the idle platens and adapted to rest by gravity on the latter, means for periodically reciprocating the active platens to cause said platens to bear upward against and lift the next higher idle platens, and then to descend until the lifted idle platens are again engaged by and rest on their supports and until the active platens again rest upon the next lower idle platens, and means for heating said platens, substantially as described.

11. In an apparatus of the nature described, the combination of a group of horizontal idle platens, laterally directed bars on said platens, upright corner posts having 60 slots for receiving said bars, active platens alternating with the idle platens and adapted to rest by gravity on the latter, upright hanger bars joined to the active platens, yokes joined to said hanger bars, means for reciprocating the yokes to cause said platens to bear upward against and lift the next higher idle 65 platens and then to descend until the lifted idle platens are again engaged by and rest on their supports and until the active platens again rest upon the next lower idle platens, and means for heating said platens, substantially as described.

12. In an apparatus of the nature described, the combination of a group of horizontal idle platens, laterally directed bars on said platens, upright corner posts having 70 slots for receiving said bars, active platens alternating with the idle platens and adapted to rest by gravity on the latter, upright hanger bars joined to the active platens, yokes joined to said hanger bars, means for reciprocating the yokes to cause said platens to bear upward against and lift the next higher idle 75 platens and then to descend until the lifted idle platens are again engaged by and rest on their supports and until the active platens again rest upon the next lower idle platens, and means for heating said platens, substantially as described.

joined to the active platens, yokes joined to said hanger bars, upright reciprocatory suspension rods in operative relation with said yokes for lifting the latter during a part 5 of each reciprocation of said rods, and means for heating said platens, substantially as described.

12. In an apparatus of the nature described, the combination of a group of idle platens supported to permit up-and-down movement and spaced from each other sufficiently to leave between them spaces greater than the thickness of the below-mentioned active platens, active platens alternating 15 with the idle platens and adapted to rest by gravity on the latter, upright hanger bars joined to the active platens, yokes joined to said hanger bars, horizontal end frame pieces, bearings on said frame pieces, reciprocatory suspension rods slidable in said bearings and in operative relation with said yokes for lifting the latter during a part of each reciprocation of said rods, and means 20 for heating said platens, substantially as described.

13. In an apparatus of the nature described, the combination of a group of horizontal idle platens, upright corner posts formed for supporting said platens with 25 spaces between them greater than the thickness of the below-mentioned active platens, active platens alternating with the idle plat-

ens and adapted to rest by gravity on the latter, suspension rods in operative relation with the active platens for raising said platens during a part of each reciprocation and lowering the active platens during another part of the reciprocation of the suspension rods, a pitman coupled to each suspension rod, a crank coupled to each pitman, means 35 for rotating said cranks, and means for heating said platens, substantially as described.

14. In an apparatus of the nature described, the combination of a group of horizontal idle platens supported to permit up-and-down movement and spaced from each other sufficiently to leave between them spaces greater than the thickness of the below-mentioned active platens, active platens alternating 45 with the idle platens and adapted to rest by gravity on the latter, means yieldingly joined to the active platens for reciprocating said platens to cause them to bear upward against and lift the next higher idle platens and then to descend until the 50 lifted idle platens are again engaged by and rest on their supports and until the active platens again rest upon the next lower platens, and means for heating said platens, substantially as described.

In testimony whereof I have signed my name this 9th day of November, in the year one thousand nine hundred and twenty-one.

CHARLES G. GLADDEEN.
